UNITED STATES PATENT OFFICE.

THOMAS D. WORRALL, OF WASHINGTON, DISTRICT OF COLUMBIA.

TYPE-WRITING AND MATRIX-MAKING MACHINE.

SPECIFICATION forming part of Letters Patent No. 339,724, dated April 13, 1886.

Application filed April 30, 1885. Serial No. 163,982. (No model.)

To all whom it may concern:

Be it known that I, THOMAS D. WORRALL, a citizen of the United States, residing at Washington, in the District of Columbia, have invented certain new and useful Improvements in Type-Writing and Matrix-Making Machines, of which the following is a specification, reference being had therein to the accompanying drawings.

10 My invention relates to improvements in type-writing machines.

The object of my invention is to connect the impression key or keys of a type-writing machine with a lever adapted to be operated to bring the type into printing contact with the paper by means of a treadle and foot-power.

Referring to the drawings, Figure 1 is a front elevation of my machine, showing the operating-lever and the treadle for moving the same. Fig. 2 is a detached sectional view. Fig. 3 is a rear view of a portion of the operating-lever and the operating and retaining pawls. Fig. 4 is a top or plan view of my improved machine.

25 A indicates the frame of the machine, mounted on suitable supports, B, in any convenient manner.

C is a bracket or cross bar secured to the top of the frame A, in which the type-carrying disk is suspended above the paper-carrying table, and capable of being readily moved around on its axis or support by taking hold of the knobs E E to bring the proper type or letter under the impression-key.

35 F is a lever pivoted at one end to the post G, said post being secured to the frame A.

H is a bolt or bar secured to the lever F, the lower end of which passes through a lug or staple, a, and is provided with a screw-nut, b, 40 at its lower end.

I is a spiral spring, which surrounds the bolt H, the upper end of which impinges against the head c of the bolt, while the lower end of said spring rests on the upper side of the lug or staple a.

45 By this construction it will be noticed that the lever F is steadied and guided in its upward and downward movement, while the tension of the spring can be adjusted by the screw-nut b to return the lever to a raised or

elevated position and ready to bring the next letter into printing contact with the paper.

As a further safeguard, and to insure a true upward and downward motion of the lever, so as to bring the impression-keys squarely down onto the type-pins I secure to the under side of the lever F the bar or pin d', and adapt it to work snugly within the socket b', secured to the frame of the machine.

The outer end of the lever F is connected 60 to the treadle K by means of the rod L, and by this means the lever is worked up and down to bring the impression-keys in contact with the type-pins, and also to move the paper-carriage by the foot of the operator, a spiral 65 or other suitable spring, M, being arranged in any convenient manner to return the treadle K to an elevated position.

N is an arm or bar attached to the lever F, in which are secured the impression-keys O, 70 said keys being vertically adjustable in said bar by means of the screw-threads on said keys, to adapt them to impinge on the type-pins P, of different lengths, as occasion may require.

75 R is an adjustable screw-bolt secured in the bar N, the lower end of which is adapted to impinge on the upper edge of the pawl-lever S, said pawl-lever being pivoted at one end to the frame A, while the other end is operated 80 upon by a spiral spring, d, which returns the pawl-lever to an elevated position.

The pawl-lever S is provided with an operating-pawl, T, which engages with a rack-bar, U, on the paper-carriage, and when the lever is depressed moves the paper-carriage V forward one or more notches, to space the distance between the letters, the carriage being held in its forward or advanced position by the retaining-pawl W.

90 A' is a lever pivoted in the frame of the machine, and is connected to the retaining-pawl W by means of the bolt e, which passes through a slot, f, in the frame A, and by which means the pawl W can be held out of engagement with the rack-bar.

The operating-pawl T is held out of engagement with the rack-bar by means of the lock or latch g, the arm g' of said pawl being pushed back, and the latch g turned around, so as to 100

hold the pawl T out of engagement with the rack-bar, thus permitting the paper-carriage to be drawn back to form a new line of printing by the action of a spring, in the usual manner.

The throw of the pawl-lever to move the paper-carriage the proper distance for spacing letters of different size is effected in the following manner. As before indicated, the bolt R is screw threaded, and is adjustable in the arm N, and in order to space for small or narrow letters the bolt R is raised or screwed up, so it will impinge but slightly on the pawl-lever S before the impression is made, thus 15 moving the paper-carriage forward one notch or tooth. Where spacing for wide letters is required, the bolt R is screwed down, so it will come in contact with the pawl-lever and force it down farther than in spacing for narrow 20 letters, thus moving the paper-carriage forward two or more notches, as occasion may require. The spacing of the letters may also be effected by having the bolt R rigidly attached to the bar N, and by bringing the lever 25 F in contact with a stop-pin adapted to be adjusted in the perforated bar B'. This will limit the movement of the lever F, and bring the pin or bolt R more or less in contact with the pawl-lever. A further adjustment 30 to effect the throw of the lever F may be made by securing the lower end of the rod L to the different staples or fastenings 1 2 3 of the treadle K. The paper-bed is moved forward to effect the spacing between the lines by 35 means of the screw-shaft C, working in bearings in the side of the frame, and connected to the paper-bed D' by the half nut E'. This construction enables me to lift the paper-bed out of engagement with the screw on the shaft C, 40 and to readily bring the paper-bed into position for printing a new page.

It will be noticed that after the proper type has been brought under the impression key O, which is the printing center, the paper-carriage is moved forward, and the impression made by the type by the downward motion of the lever F operated by foot-power. This enables me to bring the type in contact with the paper or other material to be printed upon 45 50 with considerable force, and permit of a large number of carbon copies being taken at once or in the one operation.

In practice I may reverse the operation of moving the paper-carriage—i. e., I may form the impression by the downward motion of the lever F, and arrange the operating parts so that the paper-carriage will be moved by the return or upward movement of the lever F.

The type-carrying disk or segment thereof suspended over the paper-bed, the adjustable impression pin or key, the type-carrying pins of different lengths, and the adjustable pin for operating the pawl-lever are shown, described, and claimed in an application filed by me April 18, 1885, Serial No. 162,279, and to such features I lay no claim in this application.

Having thus described my invention, what I claim, and desire to secure by Letters Patent, is—

1. In a type-writing machine, a disk carrying a plurality of rows of type-pins, in combination with a lever operated by a treadle and carrying an arm in which are arranged a plurality of impression-keys to impinge on the type-pins, as set forth. 70

2. In a type-writing machine, a lever pivoted to the side of the machine and adapted to be operated by a treadle, as described, said lever being provided with an arm carrying adjustable impression-keys, in combination with 80 type-pins, pawl-lever, and carriage-rack, as set forth.

3. In a type-writing machine, a pawl for engaging the rack-bar of the paper-carriage, in combination with a treadle-lever which operates the type-pins to form the impression, the throw of said lever being adjustable, substantially as described, to regulate the spacing of the letters. 85

4. In a type-writing machine, the impression-lever F, paper-carriage, and connections, as set forth, in combination with the perforated bar B', and a suitable stop-pin inserted in said bar, whereby the throw of the lever is adjusted to move the paper-carriage more or 90 less to space the letters. 95

In testimony whereof I affix my signature in presence of two witnesses.

THOS. D. WORRALL.

Witnesses:

N. D. ADAMS,
MARY BARKER.
